UNITED STATES PATENT OFFICE.

WILLIAM E. HUGHES, OF CLYDE, OHIO.

BURIAL-CASKET.

1,085,736.

Specification of Letters Patent.

Patented Feb. 3, 1914.

Application filed April 26, 1911. Serial No. 623,460.

To all whom it may concern:

Be it known that I, WILLIAM E. HUGHES, a citizen of the United States, resident of Clyde, county of Sandusky, and State of Ohio, have invented a new and useful Improvement in Burial-Caskets, of which the following is a specification, the principle of the invention being herein explained and the best mode in which I have contemplated applying that principle, so as to distinguish it from other inventions.

My invention relates to burial caskets and especially to caskets adapted to be inserted into and sealed in crypts of mausoleums, and particularly that class of mausoleums in which a circulation of air is provided for the desiccation of the contents of the casket.

A particular object is to provide such a casket with means for allowing the circulation of air therethrough.

The object is the attainment of such a purpose in a simple, efficient and inconspicuous manner.

The said invention consists of means which are hereinafter fully described and particularly pointed out in the claims.

The annexed drawing and the following description set forth in detail certain means embodying my invention, the disclosed means, however, constituting but one of various mechanical forms in which the principle of my invention may be applied.

In said annexed drawings:—Figure 1 is a side elevation of a casket embodying my invention. Fig. 2 is a vertical section of the same. Fig. 3 is an enlarged vertical section of another detail.

Referring to the drawings, Fig. 1 represents a conventional type of burial casket A, having the base a' , sides a'' and lid a''' . The base is provided with a plurality of supports, in this case illustrated, for the pur-

poses in hand, as ball-bearing casters b . To each of the sides a'' of the receptacle are attached a plurality of aligned brackets C. Each of these brackets is formed with a centrally positioned longitudinally extending opening c' , and each of these openings registers precisely with an opening a^4 in the side of the receptacle. The brackets are further provided with laterally disposed openings c^2 in the usual manner, these being adapted to receive a bar handle D. This handle is likewise provided with a transversely extending opening precisely registering with the opening c' in the bracket in the opening a^4 in the side of the receptacle. In this manner, a free circulation of air is permitted through the sides of the casket, as will be readily appreciated.

Having fully described my invention, what I claim and desire to secure by Letters Patent is:—

1. A burial casket comprising a receptacle, a handle therefor, said handle being provided with an opening communicating with the interior of said receptacle.

2. A burial casket comprising a receptacle; a plurality of brackets secured thereto; handles secured to said brackets, said brackets and handles being provided with registering openings communicating with the interior of the receptacle.

3. A burial casket comprising a receptacle, a plurality of brackets secured thereto, and handles secured to said brackets, said brackets being provided with openings communicating with the interior of said receptacle.

Signed by me, this 22 day of April, 1911.

WILLIAM E. HUGHES.
